UNITED STATES PATENT OFFICE

2,427,797

BUCKLE AND STRAP

Francis J. Mack, Camden, N. J.

Application April 10, 1944, Serial No. 530,365

1 Claim. (Cl. 24—177)

1

This invention aims to provide novel means whereby a belt, or equivalent structure, may be adjusted to a predetermined length and held in that condition, it being possible to slack away the belt, without rendering the end portions of the belt free of each other.

The invention aims, further, to provide novel buckles capable of carrying out the operation alluded to.

Another object of the invention is to provide a novel belt and buckle combination accomplishing the slackening away of the belt, as hereinafter alluded to.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a belt and buckle combination constructed in accordance with the invention;

Fig. 2 is an elevation wherein the device of Fig. 1 is viewed edgewise;

Fig. 3 is an elevation showing one form of buckle capable of being embodied in the invention;

Fig. 4 is a longitudinal section of the buckle depicted in Fig. 3;

Fig. 5 is an elevation showing a modified buckle, parts being broken away.

Fig. 6 is a transverse section showing a modification applicable to the buckles disclosed in Figs. 3 and 5;

Fig. 7 is an elevation showing another modification of the buckle, the buckle of Fig. 7 resembling the buckle of Fig. 3, and being anchored pivotally on a flexible element.

Figure 8 is an elevation of the modification illustrated in Figure 6.

Referring to the form shown in Figs. 1, 2, 3, and 4, there is shown a buckle, made of any material having the necessary rigidity and strength, the buckle comprising a first member 1, including a cross bar 2. Tongues 3 are rigidly connected to the ends of the cross bar, the tongues being

2

inset, adjacent to the cross bar, as shown at 4. The terminal portions 5 of the tongues 3 are disposed approximately at right angles to the cross bar 2.

5 The drawings disclose a second member 6, including a transverse head 7 and an arm 8 projecting from the intermediate portion of the head and disposed substantially at right angles to the head. A means is provided for mounting 10 the arm 8 pivotally on the intermediate portion of the cross bar, said means, in the preferred embodiment of the invention, being an eye 9.

The tongues 3 are long enough to overlap the head 7.

15 In the modification disclosed in Figure 5, parts hereinbefore described have been designated by numerals already used, with the suffix "a." The arm 8a is integrally connected with the cross bar 2a, as shown at 23, and is connected rigidly to 20 the head 7a, by riveting shown at 24. The tongues 3a are pivotally connected to the ends of the cross bar 2a for swinging movement toward and away from the head 7a. The pivotal mounting of the tongues 3a on the cross bar 2a is designated by 25 the reference numeral 50.

In the form shown in Fig. 6 and Figure 8, parts hereinbefore described have been designated by numerals already used, with the exponent "b." The tongues 3b overlap the head 7b. The head 7b 30 is provided at its ends with rectangularly disposed fingers 10, which project toward the opposite surface of the head. Except for the addition to the head of the fingers 10, the buckle illustrated in Figures 6 and 8 is like that described above, and illustrated in Figures 1 through 4.

In the modification shown in Fig. 7, parts hereinbefore described have been designated by numerals already used, with the exponent "c." The 40 eye 8c of the arm 8c has an extension 11, extended outwardly with respect to the cross bar 2c.

The extension 11 has an opening adapted to receive a rod 12 or other anchorage element, located in a tubular loop or socket 14 on a flexible member 15, the loop or socket 14 being provided with notches 22 which expose portions of the anchorage rod 12, the extensions 11 of the arms 8c being received in the notches.

The form shown in Fig. 7 is peculiarly adapted 50 for use in connection with surgical bands and similar articles, which must be of considerable width, in many instances.

Reverting to Figs. 1 and 2, the drawings show a separable connection of the buckle type, including a pair of straps 16 and 19, the word

"strap" being used to indicate any construction to which any of the buckles are applicable, and imposing no limitation as to width or structural material.

The cross bar 2 is pivotally received in a loop or eye 17 of the strap 16, that strap having a transverse keeper 18, for the reception of the free end of the strap 19. The arm 8 passes through an elongated longitudinal slit 20 in the strap 19. The strap 19 is provided with pairs of holes 21, spaced apart longitudinally of the strap, the holes of each pair being disposed on opposite sides of the slit 20. The head 7 engages the outer surface of the strap 19, that is, the surface of that strap which is remote from the loop 17 of the strap 16. The tongues 3 are engaged in any selected pair of holes 21.

Under the conditions last above described, the strap structure 19-16 is held at a predetermined length. When the tongues 3 are disengaged from the holes 21, the straps 19 and 16 are relatively slidable, longitudinally, until the arm 8 engages the strap 19 at the right-hand end 50 of the slit 20 in Fig. 1. The straps, then, have been slackened away without detaching them one from the other. The structure is peculiarly useful in connection with belts, but is not confined to that use.

The arm 8 is flattened, as shown best in connection with the arm 8b of Fig. 6, and the arm, therefore, will slide readily in the slit 20, and the slit need not be of objectionable width.

In the form shown in Fig. 6 and Figure 8, the fingers 10 cooperate with the opposite longitudinal edges of the strap 19b, and aid in holding the strap in shape and in place, especially if the strap is somewhat thin.

The modified forms of buckle, of course, are applicable to strap construction depicted in Figs. 1 and 2.

Generally considered, the device includes a

separable connection of the buckle type, including a pair of straps 19 and 16, the strap 19 having an elongated longitudinal slit 20, and having holes 21 disposed on opposite sides of the slit.

5 The buckle is permanently but pivotally assembled, by means of the loop 17, with the strap 16, the buckle including tongues 3, engageable in the holes 21. The buckle, moreover, includes a part, such as the arm 8, passing through the slit 20, the strap 19 being slideable on the tongue until the tongue engages the strap 19 at one end 50 of the slit 20, thereby to permit the straps 16 and 19 to have relative longitudinal movement without detaching them one from the other.

10 15 In all of its forms, the device is simple, but will be found to consummate the ends outlined in the opening portion of this specification, and touched upon elsewhere therein.

What is claimed is:

20 A buckle, comprising a cross-bar, tongues each rigidly connected at one end to the ends of the cross-bar, the other ends of the tongues being free, a head spaced from the cross-bar in parallel relation thereto, an arm rigidly connected at one end to the head intermediate the ends of the head, the arm being pivotally connected at its other end to the cross-bar, and the free ends of the tongues overlying the head.

FRANCIS J. MACK.
